UNITED STATES PATENT OFFICE.

STEPHEN THORNE, OF NEW YORK, N. Y., ASSIGNOR TO MARIE E. THORNE,
OF SAME PLACE.

IMPROVEMENT IN DICE-BOXES.

Specification forming part of Letters Patent No. 177,438, dated May 16, 1876; application filed
March 11, 1876.

To all whom it may concern:

Be it known that I, STEPHEN THORNE, of New York city, have invented an Improved Dice-Box, of which the following is a specification:

This invention relates to that class of dice-boxes in which the dice are confined within an inclosure, thereby preventing their being tampered with.

The invention consists, principally, in a rubber disk or diaphragm, upon which the dice rest, said disk being the spring or power whereby the dice are thrown—that is, the diaphragm being depressed in the center, by means of mechanism attached thereto for that purpose, the dice are caused to be disturbed or displaced by tumbling to the center of the disk, which, when released, throws them to the top of the case or shade in which they are inclosed.

In the accompanying drawings, Figure 1 is a perspective, and Fig. 2 a sectional, view. Fig. 3 shows the ring which secures the shade and the rubber disk in position.

A is a glass shade or cover, in which the dice are confined. B is the base, to the top of which is attached the rubber disk or diaphragm which throws the dice. The base B may be made of metal or other suitable material. C represents the rubber disk, diaphragm, or spring upon which the dice rest, and is secured to the top of the base B by a rubber ring, D, to which it is connected. E is an open cap or ring, with an inverted flange, which holds the glass shade in position, and, at the same time, acts as a binder to the rubber disk or spring C. F is a button, which is secured to the center of the disk C, and to which is se-

cured the operating mechanism for depressing the diaphragm C. G is a cord or wire attached to the button F, the opposite end being secured to a lever, whereby the rubber disk is depressed when the dice are to be thrown. H is a lever, to which the cord or wire G is attached, and by pushing down the lever, and then releasing it, the dice are thrown.

The operation is as follows: To throw the dice the lever H is forced down, thereby depressing the diaphragm C, causing the dice to be disturbed and to tumble to the center of the diaphragm, which makes it impossible to tamper with the dice or throw a desired number. Upon releasing the lever the recoil of the diaphragm throws the dice to the top of the shade, when they fall upon the disk, which immediately assumes its horizontal position after being released.

Having thus fully described my invention, what I claim as new, and desire to secure by Letters Patent, is—

1. The dice-box herein described, consisting of the base B, the rubber disk C, and glass cover A, in combination with the lever H and cord G centrally secured to said disk, substantially as and for the purpose set forth.
2. In a dice-box having a transparent cover, an elastic disk, on which the dice are supported, connected with operating mechanism by which the disk may be centrally depressed and suddenly released, substantially as described.

STEPHEN THORNE.
